DROP HAMMER

Reginald P. Fitzgerald, Braintree, Mass., assignor to Pneumatic Drop Hammer Company, Braintree, Mass., a corporation of Massachusetts

Application May 21, 1945, Serial No. 594,967

2 Claims. (Cl. 78—37)

1

This invention relates to improvements in drop hammers of the type disclosed in Patent No. 1,924,545 granted August 29, 1933 to William H. J. Fitzgerald and Reginald P. Fitzgerald in which the ends of the hammer comprise means slidably fitting upon suitably spaced vertical cylindrical guides.

One of the objects of the invention is to provide means for adjusting one of the cylindrical guides to insure accuracy and freedom of movement of the hammer. Such adjustment is particularly desirable when the drop hammer is employed in forging hot material in which case variations in temperature to which the hammer is subjected causes lengthwise expansion or contraction of the hammer which will cause undue friction between the bearings of the hammer and the columns which will interfere with its freedom of movement.

In other usual types of drop hammers the ends of the hammer are guided in vertical ways and in order to compensate for expansion and contraction of the hammer, when subjected to differences in temperature, the guides of one or both ends of the hammer are backed by adjustable pairs of shims and if the adjustment of the respective shims is not accurately made binding of the hammer during its dropping movement will result or such improper looseness of contact permitted either of which will interfere with the accuracy of movement of the hammer.

It is the object of the present invention broadly to maintain continuous vertical movement of one end of the hammer by guiding one end of the hammer accurately upon the vertical cylindrical column and by providing means for adjusting the other columns in the manner above described or which may be accomplished by providing adjustable V-shaped guiding means for the other end of the hammer which will permit not only such adjustment as to compensate for the expansion and contraction of the hammer, when subjected to changes in temperature, but which by relative adjustment of the guides for one end of the hammer will permit lateral adjustment of that end of the hammer by reason of its pivotal movement about the axis of the cylindrical non-adjustable column.

Another object of the invention is to provide a double-acting drop hammer having a vertically movable drop hammer and a cooperating vertically movable anvil the ends of each of which are provided with means fitting and slidably movable upon vertical cylindrical columns, with means located in approximately the plane of impact of the hammer and anvil for bending one of said

2

columns sufficiently to compensate the longitudinal expansion and contraction of the hammer and anvil and thereby insure the freedom of movement of each.

5 The invention is illustrated herein as embodied in a double-acting drop hammer construction of the type shown in my prior Patent No. 1,990,478 for improvements in drop hammers, February 12, 1935, which comprises a drop hammer which is 10 raised by pneumatic pressure and a cooperating vertically movable anvil which is forced upwardly by pneumatic pressure during the dropping of the hammer and caused to meet the hammer at a predetermined plane of impact.

15 Another object of the invention is to provide the bendable column at approximately the plane of impact with a narrow section which will facilitate the flexion of the column in the plane of the axes of the column together with means for preventing the bending of the column in any other direction.

20 A further object of the invention is to provide a construction in which the means for bending the column comprises a split ring or bushing adapted 25 to embrace the reduced portion of the column with a ring surrounding the bushing having an extension adjustably secured to the frame of the hammer and so constructed as to prevent lateral displacement of the column.

30 These and other objects and features of the invention will more fully appear from the following description and the accompanying drawings and will be particularly pointed out in the claims.

35 Illustrative embodiments of the invention are shown in the accompanying drawings, in which,

Fig. 1 illustrates a front elevation of a double-acting drop hammer embodying the invention;

Fig. 2 is an enlarged detail view of the lower portion of the drop hammer construction shown 40 in Fig. 1 illustrating the means for adjusting one of the columns, partially in vertical section, portions of the frames of the standard being broken away to illustrate parts otherwise hidden by the frame;

Fig. 3 is a horizontal sectional view on line 3—3 45 Fig. 2, viewed downwardly, showing the anvil as supported upon and actuated by two pneumatically actuated cylinder and piston mechanisms of the character disclosed in the prior patent aforesaid;

Fig. 4 is an enlarged detail horizontal sectional view of the column and the portion of the adjusting means surrounding the same on line 3—3

55 Fig. 2 viewed downwardly;

Fig. 5 is an enlarged detail vertical sectional view on line 5—5 Fig. 4;

Fig. 6 is a horizontal sectional view of one of the columns and the end section of the hammer surrounding it and illustrating the means for retaining the compressible bushing within the extension of the hammer;

Fig. 7 is a vertical sectional view on line 7—7 Fig. 6, the column being shown in elevation; and,

Fig. 8 is a horizontal sectional view of the invention showing one extension of the hammer as mounted upon a vertical column and the other end of the hammer mounted in vertical guides adapted to be adjusted to compensate for expansion and contraction of the hammer and/or adjustment of that end of the hammer laterally about the axis of the column.

The drop hammer construction illustrated in the drawings comprises a base 1, which desirably is fabricated from structural steel members having four fabricated piers 2, 3, 4, and 5, extending upwardly therefrom with a plate 6 mounted on said base forming the support for anvil-actuating cylinders 7 and 8 of the character described in my prior patent. The cylinders 7 and 8 are respectively provided with pistons 9 and 10 having enlarged heads 11 which support opposite ends of the vertically movable anvil 12. The upper end of the anvil is provided with a dovetail groove 13 in which the anvil die block 14 is secured by a suitable wedge 15. The anvil-actuating cylinders 7 and 8 may be cast in one piece and the adjacent walls of the cylinders and the supporting plate therebeneath provided with a passage 16 in which conduits for supplying air under pressure to the upper and lower chambers of the cylinder and the exhaust from the upper chamber of the cylinder may be located and having a lateral extension 17 communicating with a suitable housing containing valve mechanism for controlling the supply of air under pressure to the upper chambers of the anvil-actuating cylinders of the character disclosed in my prior Patent No. 2,220,037, October 29, 1940, and which need not be more fully described herein. Rectangular deck plates 18 and 19, which extend respectively over the piers 2, 3, and 4, 5, have welded to them intermediate of the length of their inner sides vertical preferably cylindrical hollow bosses 20 and 21 in which the lower ends of vertical cylindrical guiding columns 22 and 23 for extensions of the anvil and hammer are mounted. The frame of the hammer comprises four vertical standards 24, 25, 26, and 27 having respectively vertical inner walls 28 preferably in axial alignment with the columns 22 and 23 respectively. Parallel walls 29 extend at right angles to the walls 28 a short distance from the inner edges of the columns 28 and front and rear end walls 30 preferably converge upwardly as illustrated in Fig. 1.

The lower ends of the column walls 28, 29 and 30 and the deck plates 18 and 19 are secured to the respective piers 2, 3, 4, and 5 by angle plates 31, 32 and 33 respectively the vertical walls of which are welded respectively to the plates 28, 29 and 30 and the horizontal walls of which are secured to the deck plates and piers by bolts 34. A suitable overhead beam or arch 35 in the form of a thick rectangular plate connects the upper ends of the standards 24, 25, 26, and 27. The upper ends of the cylindrical guiding columns 22 and 23 are mounted in suitable sockets 36 in the overhead beam 35 midway of the distance between the vertical standards. A pneumatic ham-

mer-lifting cylinder 37, which is mounted upon the overhead beam 35 and is provided with a base 38 having an integral extension 39 in which the valve controlling the supply of air under pressure to the cylinder 37 and the exhaust therefrom are mounted of the character illustrated in my prior patent No. 2,220,037 aforesaid and which need not be further described.

The piston 40 of the hammer-lifting cylinder 37 is mounted in a suitable bearing 41 centrally of the overhead plate 35 and its lower end is secured through a suitable coupling 42 to the hammer 43. The hammer is provided with end extensions 44 which are counterbored downwardly nearly to the lower ends of said extensions to receive preferably bronze bushings 45 adapted to be progressively condensed by repeated impacts of the hammer to maintain a perfect fit upon the vertical columns as described in the prior Patent No. 1,924,545. Desirably the upper ends of the counterbores are slightly enlarged as shown in Fig. 7 to receive a washer 46 which is held in place by a spring ring 47 overlying the washer and seated in a suitable groove in the extension 44 as illustrated in Figs. 6 and 7.

The anvil likewise is provided with extensions 48 which are similarly provided with bushings slidably fitting the columns 22 and 23 respectively. By reason of this construction accurate vertical reciprocations of the hammer and anvil upon the cylindrical guiding columns 22 and 23 is assured.

However, where the double-acting hammer is employed in hot forging variations in temperature of the anvil and part of the hammer causes such expansion and contraction lengthwise of the hammer as to produce a binding of the bearings and it is the principal object of the present invention to provide means for adjusting the column 23 in such manner as to compensate for the slight variations in the lengths of the hammer and anvil respectively. In order to accomplish such adjustment means are provided for bending the column 23 in the vertical plane of the axes of the columns 22 and 23 sufficiently to compensate for such variations in the length of the anvil and hammer respectively.

In the constructions illustrated in Figs. 1—7 inclusive the means comprises a horizontally adjustable member mounted upon the frame of the machine having an integral circular portion embracing the column 22 at approximately the plane of impact of the hammer and anvil with means for moving said adjustable member toward and/or toward and from the column 23.

In the preferred construction illustrated herein in a short section 49 of the column 22 is made of somewhat decreased diameter to lend flexibility to the column. A split ring bushing formed in two halves 50 and 51 having an internal diameter fitting upon the reduced portion 49 and an external diameter slightly larger than the diameter of the column 22 is mounted upon the reduced section 49 of the column 22 and are provided respectively with outwardly extending annular flanges 52 and 53. The adjusting member comprises a rectangular adjusting plate 54 having an extension 55 terminating in a thickened annulus 56 which tightly embraces the split ring bushing 50, 51 and is adjustably mounted upon the standards 2 and 3 of the frame.

As illustrated in the drawings a horizontal plate 51, which is located slightly below the plane of impact of the hammer and anvil, is provided with downwardly extending flanges 58 which are

welded to the vertical walls 29 of the standard and rabbeted keeper plates 59 are bolted to the plate 51, the rabbets in the plates 59 forming ways for the rectangular adjusting plate 54. The adjusting plate 54 is provided in proximity to its edges with slots 60 through which locking bolts or screws 61 extend and engage the supporting plate 51. The supporting plate 51 is provided adjacent its outer edge with an upwardly extending integral boss 62 and the adjusting plate is provided with an upwardly extending boss 63 complementary to the boss 62. An adjusting screw 64 extends through the boss 62 and engages complementary internal screw threads in the boss. The outer end of the screw 64 is provided with an angular head 65 adapted to be engaged by a suitable wrench. The inner end of the screw 64 preferably may engage the boss 63 upon the adjusting plate so that by turning up the screw it will bend the column 22 inwardly, the column 22 being normally spaced apart from the column 23 sufficiently to permit free vertical movement of the hammer and anvil when they are in a heated condition and the adjustment is provided by bending the column 22 toward the column 23 when the hammer and anvil contract by decrease in temperature.

However, means may be provided for moving the adjusted plate in both directions. This is illustrated in Fig. 3 in which the shank of the screw 64 extends through a vertical recess 66 in the boss 63 of the adjusting plate 54 and a collar 67 which is fixedly secured to the screw fits within and engages the complementary walls of the recess 66.

When the adjusting plate 54 is moved to the desired required position to insure free vertical movements of the hammer and anvil it can be locked in such adjusted position by firmly setting up the nuts 61.

Lateral, forward or rearward bending of the column is prevented by reason of the fact that the edges of the adjusting plate 54 closely engage the ways in which it is mounted and together with the bolts which clamp it to the plate 51 hold the plate and the annulus which embrace the column from any lateral movement.

Means are also provided for preventing lateral movement of the column 23. As illustrated herein suitable abutment members 68 and 69 are clamped by suitable bolts 70 upon alined extensions 71 of the vertical walls 28 of the standards approximately in the plane of impact of the hammer and anvil.

By reason of the adjustment of the cylindrical column 22 above described proper free reciprocation of the hammer may be maintained without any such tolerance in the sliding engagement of the extensions of the hammer and anvil as would otherwise be required and accuracy of movement of the hammer and anvil at all times assured. This is particularly important in cases where the hammer and anvil are provided with complementary dies the accurate registry of which is essential.

In its broad aspect the object of the invention is to provide a drop hammer having a vertical cylindrical guiding column to insure accurate guiding of one end of the hammer with means for adjusting the other end of the hammer to compensate for expansion and contraction of the hammer and/or the anvil and which may also include lateral adjustment of the hammer about the axis of the fixed cylindrical column. Such an embodiment of the invention is illustrated in

Fig. 8 which shows a horizontal sectional view of the standards of a drop hammer, the hammer mounted at one end upon a cylindrical column, and with adjustable angularly disposed guides engaging the opposite end of the hammer with means for adjusting the respective guides. The drop hammer construction as illustrated in Fig. 8 comprises a rectangular base 72 having a vertical standard 73 suitably secured thereto by bolts 74 and having a central arcuate wall 75 forming a recess 76 in which a vertical column 77 is mounted. The hammer 78 has an extension 79 which embraces a bushing 80 of the character above described slidably fitting upon the accurately turned column 77 and insuring accurate vertical movement of that end of the hammer. The opposite end of the hammer 78 is provided with an extension having symmetrically inclined angular end portions 81 and 82 which are adapted to be engaged by complementary angular surfaces of vertical guides for the hammer 83 and 84 which are mounted in rectangular recesses in the other standard 85 of the frame which is suitably anchored to the base 72 by bolts 86.

The guides 83 and 84 are adjustably secured to the frame as in usual constructions by machine screws extending through suitably spaced horizontal slots in the guides (not shown) with shims 87 interposed between the backs of the respective guides 83 and 84 and the vertical walls of extensions 88 of the standard, as shown in Fig. 8. Screws 89 and 90 mounted respectively in the extensions 88 at suitably spaced vertical distances apart engage the shims 87, or the guides 83 and 84 if shims are not employed. By rotating the respective screws 89 and 90 in proper directions the guides may be so adjusted as to compensate for the expansion or contraction of the hammer when subjected to variations in temperature and also may be so adjusted as to provide lateral adjustment of the hammer about the axis of the column 77.

In this construction suitable means may be provided for adjusting the anvil to cause proper registration of dies carried respectively by the hammer and anvil as will be readily apparent to those skilled in the art. The invention herein described can be applied either to a drop hammer having a stationary anvil, or to a double-acting hammer.

It will be understood that the embodiments of the invention particularly shown and described herein are of an illustrative character and that various modifications in construction and arrangement of parts may be made within the spirit and scope of the following claims.

Having thus described the invention, what is claimed as new, and desired to be secured by Letters Patent, is:

1. A double-acting drop hammer having a base, pairs of front and rear vertical standards mounted on said base, an overhead beam connecting said standards, parallel vertical cylindrical columns intermediate of the front and rear standards of the respective pairs mounted at their ends in sockets in said base and overhead beam, a vertically movable hammer, and a co-operating vertically movable anvil having end portions fitting and slidably mounted on the respective columns, a member mounted upon adjacent walls of one of said pairs of standards approximately in the plane of impact of said anvil and hammer provided with parallel horizontal guideways, an adjusting member for the

adjacent column having annular means embracing the column and an extension slidably fitting said guideways, acting to prevent forward or rearward deflection of said column, means for forcing said adjusting member longitudinally of said guideway to bend said column in a direction lengthwise of said hammer and anvil, and means for locking said member in adjusted position, and cooperating means mounted upon the other pair of standards engaging the column adjacent thereto at approximately the plane of impact of the hammer for preventing forward or rearward deflection of said standard.

2. A double-acting drop hammer having a base, vertical standards mounted on said base, an overhead beam connecting said standards forming a frame, suitably spaced parallel vertical cylindrical columns mounted at their respective ends on said base and overhead beam, a vertically movable hammer and a cooperating vertically movable anvil each having end portions fitting and slidably mounted on the respective columns, one of said columns having a narrow reduced cylindrical portion in proximity to the plane of impact of the hammer and anvil, means for adjusting said column comprising a horizontal supporting member fixedly mounted upon said frame in proximity to the plane of impact of the hammer and anvil and provided with parallel

guideways, an adjusting member having an annular end portion of larger diameter than the reduced portion of said column surrounding the same, a split ring fitting the reduced portion of the column and also fitting within the annular end portion of said adjusting member, and an extension on said adjusting member slidably fitting said guideway, cooperating means on said supporting member and extension of said adjustable member operable to force said adjustable member in a direction lengthwise of the hammer to bend said column, and means for locking the same in adjusted position.
